(57) **CLAIM**

The ornamental design for a cosmetic jar and cap with applicator, as shown and described.

DESCRIPTION

FIG. 1 is a top perspective view of a cosmetic jar and cap with applicator showing the claimed design;

FIG. 2 is a bottom rear perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an exploded view of the cosmetic jar and cap with applicator, as shown in FIG. 1;

FIG. 10 is a top front perspective view of the cosmetic jar and cap with applicator, the jar and applicator removed for clarity of illustration;

FIG. 11 is a bottom rear perspective view thereof;

FIG. 12 is a front view thereof;

FIG. 13 is a rear view thereof;

FIG. 14 is a left view thereof;

FIG. 15 is a right view thereof;

FIG. 16 is a top view thereof;

FIG. 17 is a bottom view thereof;

FIG. 18 is a cross-sectional view thereof taken along line 18-18 in FIG. 12;

FIG. 19 is a front perspective view of the cosmetic jar and cap with applicator, the cap and applicator removed for clarity of illustration;

FIG. 20 is a bottom rear perspective view thereof;

FIG. 21 is a front view thereof;

FIG. 22 is a rear view thereof;

FIG. 23 is a left view thereof;

FIG. 24 is a right view thereof;

(Continued)

FIG. 25 is a top view thereof;
 FIG. 26 is a bottom view thereof;
 FIG. 27 is a cross-sectional view thereof taken along line 27-27 in FIG. 21;
 FIG. 28 is a top front perspective view of the cosmetic jar and cap with applicator, the jar and cap removed for clarity of illustration;
 FIG. 29 is a bottom rear perspective view thereof;
 FIG. 30 is a front view thereof;
 FIG. 31 is a rear view thereof;
 FIG. 32 is a left view thereof;
 FIG. 33 is a right view thereof;
 FIG. 34 is a top view thereof; and,
 FIG. 35 is a bottom view thereof.
